WINDING MACHINE FOR GOLF BALLS
Meyer Bloom, Brooklyn, N.Y., assignor of fifty percent to
Ralph J. Atti, Cliffside Park, N.J.
Filed Jan. 19, 1965, Ser. No. 426,501
3 Claims. (Cl. 242—3)

This invention relates to winding machines in general, and more especially to winding machines for golf balls and the like, particularly to such winding machines which will wind a plurality of different kinds of windings such as one or more different basket weave type, a great circle type and the like.

Among the objects of the present invention, it is aimed to provide an improved winding machine, particularly for winding golf balls which will wind different types of windings such as, of the basket weave type as an instance and/or of the great circle type successively in different combinations depending upon the type of weave or winding desirable, in turn depending upon a predetermined setting which will continue uninterruptedly to perform the desired or required winding depth and automatically come to rest when the required winding depth or required size of ball has been produced.

These and other features, capabilities and advantages of the invention will appear from the subjoined detail description of one specific embodiment illustrated in the accompanying drawings in which

FIG. 1 is a front elevation of a machine made according to the present invention,

FIG. 2 is a rear view of a machine partly broken away,

FIG. 3 is an enlarged section on the line 3—3 of FIG. 1,

FIG. 4 is an enlarged fragmental section on the line

4—4 of FIG. 3,

FIG. 5 is a fragmental section showing a part of the control in a second position relative to the position shown in FIG. 3,

FIG. 6 is a fragmental section on the line 6—6 of FIG. 3,

FIG. 7 is a plan view of a ball after it has received a number of windings according to one setting,

FIG. 8 is a plan view of a ball after it has received a number of windings according to another setting, and

FIG. 9 is a schematic view of the several parts of the machine showing a possible wiring example of the same.

In the embodiment shown, there is provided a housing 1 having a platform 2 to receive the motor 3 which is connected by the wires 4 and 5, see FIG. 9, to the main switch 6 which is connected by the wires 7 and 8 to the main conductors 9 and 10 connected to a supply of power not shown. In the walls 11 and 12 there is journaled the slidably and rotatable shaft 13 which has a sheave 14 at one end outside of the wall 11 to receive the belt 15 which is drivingly connected to the sheave 16 of the motor 3.

The sheave 14 on the shaft 13 is disposed outside of the wall 11. On the end of the shaft 13 extending beyond the other wall 12 there is mounted the cylindrical roller 17 having a cover 18 presenting an external friction forming cylindrical surface. The cover 18 may be composed of any number of substances preferably of a material such as neoprene rubber.

On the shaft 13, between the walls 11 and 12, there is fixed the disk 19 to the upper end of which in FIG. 5 there is fixed and extending through the same the pin 20. Through the lower end of the disk 19 there is slidably mounted the pin 21 similar in construction to the pin 20. The ends of the pin 20 are provided with rotatable balls 22 and 23 to ride against the opposing surfaces of the cam plates 24 and 25 respectively. In turn on the ends of the pin 21, there are mounted the rotatable balls 26 and 27 to ride on the opposing surfaces of the cam plates 24 and

2

25. Consequently, if the cam plates 24 and 25 are set as shown in FIG. 3, with the rotation of the shaft 13, the disk 19 will rotate relative to the cam plates 24 and 25 and not disturb axial position of the shaft 13 and thereby of course not disturb the position of the roller 17 relative to the rollers 28 and 73 shown in FIG. 3.

On the other hand, the cam plates 24 and 25 are tiltably mounted on stub shafts which are journaled in the walls 29 and 30 which are disposed at right angles to the walls 11 and 12 respectively. The cam plate 24 shown in FIG. 4 is provided with the stub shafts 31 and 32 journaled in the side walls 29 and 30 respectively. The cam plate 25 is provided with similar stub shafts, one only being shown, to wit, the stub shaft 33. The cam plates 24 and 25 are tiltably mounted on the stub shafts, such as the stub shafts 31, 32 and 33 so that when the disk 19 is set in the position relative to the cam plates 24 and 25 shown in FIG. 5, the cam plates 24 and 25 will actuate the pins 20 and 21 in turn to reciprocate the shaft 13 and therewith the cylindrical roller 17.

The setting of the cam plates 24 and 25 about their stub shafts 31, 32 and 33 will be effected simultaneously since with the axes of the stub shafts 32 and 33 fixed and the crossbar 34 pivotally connected to similar portions of the cam plates 24 and 25 a parallel movement will be effected to cause the cam plate 25 to move with the cam plate 24. In the present instance, the cam plate 24 is provided with a connection 35 which has threadedly connected thereto the screw 36 connected to the pin 37 extending through the wall 11 into the cylindrical air valve 38. The air valve 38 is provided with the air lines 39 and 40 connected to the solenoid valve 41, see FIG. 3, connected to the wall 11. When the valve 38 is energized to attract the pin 37 into the position shown in FIG. 5, it will at the same time attract the cam plate 24 and due to the bar 34 tilt the cam plate 25 with it, into the position shown in FIG. 5. Thereupon the actuation of the shaft 13 will be actuated by the disk 19.

The control of the valve 38 is effected by the cam 42 mounted on the timing motor 43 which is drivingly connected by current supplied to it through the conductors 44 and 45 which extend from the motor 43 to the conductors 4 and 5 respectively. The cam 42 cooperates with the pin 46 in the micro switch box 47 which is connected to the solenoid valve 41 by the conductors 48 and 49. This switch box 47 in turn is connected to the main conductors 9 and 10 by the conductors 63 and 64 respectively.

In other words, when the double acting air valve 38 is in one position where the pin 37 is extended as shown in FIG. 3, the pin 46 is extended in current cut-off position as shown in FIGS. 2 and 9, but is yieldable to be deflected into the micro switch box 47 by the raised portion 50 of the cam 42 to actuate the double acting air valve 38 into the other position. When the cam 42, see FIGS. 2 and 9 so continues in its rotation and reaches the depressed portion 51, it will allow the pin 46 to be extended and reverse the position of the air valve 38. In other words, assuming that the current has been established in the conductors 9, 10, 4, 5 and 44, 45 the cam 42 will rotate in the direction of the arrow 52 and assuming that the position shown in FIGS. 2 and 9 is the starting position, the cam 42 will rotate a quarter of a cycle until its raised portion 50 strikes the pin 46 and deflects it to actuate the air valve 38 into the other direction. When the current is so shut off, the air valve 38 will actuate the pin 37 from the position shown in FIG. 3 to the position shown in FIG. 5 where it will actuate the plate 24 and through the bar 34, the cam plate 25 into their tilted position. Now when the shaft 13 rotated by the motor 3 continues in its rotation, it will for a half of a cycle actuate the circular disk 19 with it to cause the shaft 13 to be reciprocated and therewith reciprocate the roller 17.

When the cam 42 thus has rotated a half of a cycle or a full one hundred and eighty degrees, the raised portion 50 will have ended and the depressed portion 51 of the cam 42 again register with the pin 46 to permit the pin 46 to be released and extended into position for actuating the air valve 38 into its original position. When the valve 38 is so actuated, it will now expel the pin 37 and return it to the extended position shown in FIG. 3 where the cam disks 24 and 25 will appear at right angles to the shaft 13 and position the circular disk 19 parallel to the cam disks 24 and 25 and discontinue the reciprocation of the shaft 13 so that now the roller 17 will be maintained in one and the same position.

By this control of the shaft 13 and in turn of the reciprocation or non-reciprocation of the roller 17, the windings of the ball to be wound will intermittently be changed so that the initial ninety degree movement of the cam 42 will effect the ejection of the pin 37 into the position shown in FIG. 3 where the shaft 13 is rotated without being reciprocated and the roller 17 actuates the ball to transmit great circle windings to the ball and then when the raised portion 50 of the cam 42 actuates the pin 46 to deflect it into the micro switch box 47, it will reverse the action of the air valve 38 to withdraw the pin 37 into the position shown in FIG. 5 in which position the cam plates 24 and 25 will be tilted as shown in FIG. 5 to effect the reciprocation of the shaft 13 and therefore the reciprocation of the roller 17 to transmit a basket weave winding of the rubber band 53. Finally, when the end of the raised portion 50, after a hundred and eighty degree rotation of the cam 42 again registers with the pin 46 and the pin 46 is thereupon allowed to be ejected by registering with the low portion 51 of the cam 42, the cam 42 will be instrumental in causing the actuation of the double acting air valve 38 to allow the pin 37 again to be ejected into the position shown in FIG. 3.

Preferably, the machine is set so that for the initial ninety degree movement or quarter revolution of the cam 42, a great circle winding will be transmitted to the rubber band 53, then one hundred and eighty degrees or one half a revolution of the cam 42 be instrumental in effecting a basket weave winding of the band 53 and finally, upon completing the third quarter or third ninety degree rotation of the cam 42, a second great circle winding will be transmitted to the rubber band 53. On the other hand, the winding of a ball by a rubber band such as the rubber band 53 may start with a basket weave winding, succeeded by a great circle winding and then returned to a basket weave winding.

Still furthermore, a cam other than the cam 42 may be provided having a plurality of low and high spots alternately succeeding one another. Finally, the basket weave winding may be very small as compared to the great circle winding and vice versa, depending upon the type of ball desired. It has been found that with a great circle winding a harder or less elastic ball may be obtained than with a basket weave winding, and in turn that a smoother, uniform, spherical surface may be obtained with a basket weave winding than with a great circle winding so that if the demand is for a harder or less elastic ball, a greater number of great circle windings than basket weave windings will be required and in turn, if the demand is for a ball with an extremely smooth or perfectly spherical surface, a larger number of basket weave windings than great circle windings may be required.

The position of the cam 42 in the present machine is used to determine the starting point of a cycle. For this reason, on the cam 42 in the middle of portion 50 there is provided a contact point 54 to serve as a contact for the button 55 at the end of the lever 56 of the microswitch 57 which is connected by the conductors 58 and 59 to the light or lamp 60. This microswitch 57 in turn is connected by the conductors 61 and 62 to the main con-

ductors 9 and 10 respectively, it being assumed that the conductors 63 and 64 from the conductors 9 and 10 respectively to the microswitch 47 are parts of the main conductors 9 and 10. Consequently, when the machine is intended to be operated, the button 65 on the main switch 6 will be pressed whereupon the current will be established in the motor 3 and in the timing motor 43. The current then will also go to the microswitches 57, 47, 66 and 67.

After the switch button 65 has been depressed, and the cam 42 has been set where the contact 54 engages the contact 55, current will be established in the microswitch 57 and the lamp 60 illuminated. Immediately after the cam 42 moves so that its contact 54 clears the contact 55, the lamp 60 will become extinguished.

The current at the same time will be established in the double acting air valve 38, the microswitch 47 merely being instrumental in actuating the valve 41 of the double acting air valve 38 into one or the other position.

The microswitches 66 and 67 are connected to the main switch 6, the conductor 68 connecting the microswitch 66 directly to the main switch 6, the conductor 69 connecting the microswitch 67 to the main switch 6, and the conductor 70 connecting the microswitch 66 to the microswitch 67. Consequently, either the microswitch 66 or the microswitch 67 may break the circuit to the motor 3 and actuator 43.

The microswitches 66 and 67 and their function will hereinafter be described in detail.

The rotation of the ball in embryo 72 is rotated in the conventional way as illustrated in United States Letters Patent No. 2,694,535 of Ralph J. Atti issued Nov. 16, 1954, and comprises in addition to the cylindrical roller 17 the duplex conical roller 73 consisting of an idler having two conical rollers 74 and 75 with the diminished ends adjacent to one another mounted on the stub shaft 76 adjacent to the cylindrical roller 17. Above and preferably substantially between the cylindrical roller 17 and duplex conical roller 73, there is mounted the roller 28. The stub shaft 76 extends through the wall 12 to one side of the shaft 13 as shown in FIG. 6. The roller 28, also an idler, is preferably mounted as shown on a stub shaft 78 extending through the bracket 79 slidably mounted on the wall 12. The periphery of the roller 28 is round axially similar to an automobile tire. Preferably, the faces of the conical rollers 74 and 75 and of the roller 28 are formed of stainless steel or the like polished and smooth whereas the cover 18 on the cylindrical roller 17 is of course comparatively rough and presents a friction-creating surface. The ball in embryo 72 is mounted between these three rollers and since the conical roller 73 and idler 28 are smooth, and the cylindrical cover 18 alone transmits a definite frictional force on the ball 72, the rotation of the shaft 13 will actuate the roller 17 in turn to cause the ball in embryo 72 to rotate between the three rollers.

It is not new to produce a winding on a ball in embryo 72 between three such rollers. Similarly, it is not new to use great circle windings nor basket weave windings. However, it is new to use in one and the same machine successive winding forces of a great circle and of a basket weave on one and the same ball 72 by one and the same rubber band 53. The rubber band 53 in the present instance is wound on a supply reel 80 mounted in the bracket 81. From the supply reel 80 the rubber band 53 passes up over the idler 82, under the idler 83 mounted in the housing 1 and from the idler 83 under the cover 18 of the roller 17 on to the ball 72. Preferably in practice the beginning of the rubber band 53 is wound around the ball 72 several times and then so placed between the roller 17 and idlers 73 and 28 with the rubber band 53 coming up under the cover 18 onto the far side of the ball 72. Thereupon, if the machine is set to start with great circle windings, the initial quarter cycle or ninety degree rotation of the cam 42 will cause the great circle windings 84, see FIG. 8 to be formed on the

same. Thereafter, without removing the ball 72 from contact with the cover 18 and idlers 73 and 28 but by mere actuation of the cam plates 24 and 25 as aforesaid, the shaft 13 will be reciprocated to form basket weave windings such as the windings 85 in FIG. 7. As the diameter of the ball 72 increases, the idler 28 will exercise an elevating force on the bracket 79.

The bracket 79 will be weighted by any one or more different types of weights. As an instance, it may have mounted on it the rod 86, see FIGS. 1 and 4 on which are mounted weights such as the weights 87 and 88.

Still furthermore, should additional weight be required, the lever 89 pivotally mounted at 90 to the housing 1 may be pin and slot connected to the bracket 79 by the pin 91 on the bracket 79 extending through the slot 92 in the lever 89. On the right hand portion 93 of the lever 89, weights may be attached or suspended at will depending upon the additional weight to be supplied. In order to remove the ball 72 without difficulty, the bracket 79 may be raised by the lever 89 by merely depressing the end 94 as shown in FIG. 1.

In order automatically to bring the roller 17 and thereby the motor 3 to rest when the desired number of windings from the rubber band 53 have been accumulated, such stoppage will be achieved by the contact 95 on the bracket engaging the switch arm 96 pivotally mounted on the switch shaft 97 and in turn actuating the contact arm 98 to engage the pin or arm 99 of the microswitch 66. This contact will cause the current to the motor 3 to be interrupted.

Similarly, should the rubber band 53 break during the operation aforesaid, then due to the roller 100 resting on the rubber band 53 between the idler 83 and the roller 75, the microswitch 67 will be actuated, the roller 100 being mounted on the arm 101 pivoted at 102 and having the arm 103 in position to engage the contact 104 of the microswitch 67. The arm 103 will engage the contact 104 when the roller 100 drops due to the breaking of the rubber band 53 and thereby interrupt the current through the conductor 69, microswitch 67, conductor 70, microswitch 66 and conductor 68 to the main switch 6.

While sizes and dimensions may be immaterial to a certain extent, it may be desirable here to point out that excellent results have been achieved when the shaft 13 of the motor 3 operates at about 1000 r.p.m., the diameter of the rubber strand, strip or band 53 is about .0625" in width and .020" in thickness, the size of the ball in embryo 72 about one and one half inches in diameter before the winding is started, the oscillation or reciprocation equaling about 1725 r.p.m., whether the ball to be produced is the British or American ball with the exception that for the smaller British ball which is 1.62" in diameter with the ball in embryo 72 before the cover is attached being about 1.58" in diameter and that the larger American ball which is 1.68" in diameter, the final ball in embryo before receiving the cover is 1.60".

The material of the several parts of this machine are also immaterial to a certain extent. However, it may be desirable here to point out that excellent results have resulted when the cylindrical cover 18 is composed of neoprene rubber and the duplex conical roller 73 and the upper roller 28 are composed of stainless steel with highly polished surfaces for the faces of the duplex conical roller 73 and the upper roller 28.

Preferably also the pressure normally maintained in the double acting air valve 38 will be about fifty pounds.

For the average basket weave, the shaft 13 is moved about one quarter of an inch longitudinally. However, this distance of movement may be greater or less depending upon the yieldability or resiliency for the final ball desired by the manufacturer. If the angle of tilt of the cam plates 24 and 25 is to be greater or less, it is only necessary to turn the screw 36 and the stop pin 105, see FIG. 3, corresponding distances.

It is obvious that various changes and modifications may be made to the details of construction without departing from the general spirit of the invention as set forth in the appended claims.

I claim:

1. In a winding machine the combination of a ball in embryo, a housing, at least three rollers mounted on shafts having parallel axes journalled in said housing, at least two of said rollers at the bottom of said three rollers to support said ball, means for imparting a rotative force to the shaft of one of said lower rollers, means comprising a disc fixed to the said lower roller shaft, a first fixed pin carried by the disc and extending outwardly thereof on each side of the disc, a second pin, slidably carried by the disc, spaced from the first pin and extending outwardly of said disc on each side of the disc, a first and a second cam plate on each side of the disc and spaced therefrom a distance equal to the outward extension of the pins whereby the pins will ride upon the inner faces of the plates when the disc is rotated with its shaft, said cam plates and disc being disposed in spaced parallel relationship when the machine is in the neutral position for great circle winding, means coupled to the lower roller shaft for imparting a longitudinal action on said latter shaft, means intermittently actuating said longitudinal actuating means by tilting the cam plates with respect to the disc to bring the machine into and out of neutral position, means predetermining the actuation of said latter means into and out of neutral position, means slidably mounting the shaft of said upper roller normally to rest on the ball in embryo to cooperate with said two lower rollers to impart a great circle winding rotation to the ball when said rollers are in neutral position relative to one another and to impart a basket weave winding rotation to the ball when said one of said rollers is being reciprocated, and a reel of rubber strip having the strip extending up from it to and between said rollers to and onto the ball in embryo.

2. A winding machine according to claim 1 in which the pins are formed with friction reducing balls on each end thereof for contact with the adjacent plate faces.

3. A winding machine according to claim 1 in which the cam plates are tilted by a double acting cylindrical air valve under the control of a motor driven cam.
